LADY'S GARMENT

Austin J. Bono, Revere, Mass., assignor to Fitwel Dress Co., Inc., Boston, Mass., a corporation of Massachusetts

Application February 14, 1942, Serial No. 430,953

3 Claims. (Cl. 2—235)

The invention relates to an improvement in slacks, skirts, or the like, and is characterized by a construction permitting of ample waistline adjustment by which the garment is especially adaptable for maternity wear.

The essential object of the invention is to provide a garment having relatively wide latitude of waistline adjustment, but which will retain substantially the attractiveness of its most constricted form whatever may be the degree of its expansion within the range of afforded adjustment.

The invention can best be seen and understood by reference to the drawings in which only such portion of the garment is shown as is necessary for a proper understanding of the invention.

Fig. 1 is a front elevation of the garment in its most constricted form.

Fig. 2 is the same as Fig. 1 excepting that the front panel, later to be referred to, is dropped.

Fig. 3 is a front elevation of the garment after a slight let-out, or expansion, at the waistline.

Fig. 4 is the same as Fig. 3, with the front panel dropped.

Fig. 5 is a general perspective of the garment, showing many of the operating parts later to be referred to.

Fig. 6 is a front elevation of the garment as approach is made to the full extent of expanded waistline.

Fig. 7 is the same as Fig. 6, with the panel dropped.

Fig. 8 is a view showing the garment with maximum expansion at the waistline as provided by certain manipulation of the means affording such adjustment, and to which special reference will hereinafter be made.

Fig. 9 is the same as Fig. 8, with the panel dropped.

Referring to the drawings—1 represents the back portion of the garment and 2, 2 its leg, skirt, or lower portions.

The back portion of the garment along its sides is provided with winged extensions 3, 3'. These extensions are generally triangular in form, each starting from the side seam of the leg portions of the garment at points 4 well down from the waistline, and thence extending forward to form a partial front closure for the garment. These extensions may have other than triangular form as may be desired.

Overlapping the extensions 3, 3', and forming the front to the body of the garment is a panel 5. This panel extends upwardly from the leg portions of the garment from about the same points

5 from which spring the extensions 3, 3', and the panel is capable of being turned up and down. When turned up and retained, as will later be explained, it overlaps the extensions 3, 3', closing the front of the garment; and co-operates with the extensions and back of the garment, to form, when the panel is in closed position, plackets 6, 6' at either side of the garment adjacent the side edges of the closed panel.

The garment is held up by a waistband 7 of which the part 8 forms a top edge finish to the back portion 1 of the garment at the waistline and is extended to form a like finish along the top to each of the respective extensions 3, 3'. Thence the waistband is extended by free ends or straps 10, 10', and these, when connected, complete the belting of the waistband, snugly embracing the wearer, and operating to hold up the garment, after which the panel 5 may be turned up and fastened to occupy a normal finished position, closing the front of the garment, and co-operating with its back portion 1 and front extensions 3, 3', to form the respective plackets.

The free end, or strap forming portions 10, 10' of the waistband are adjustably connected in the following manner. The portion 8 of the waistband, and especially the portion thereof, extending over the respective tops of the wing forming extensions 3, 3', are provided, respectively, with exterior sets of circumferentially spaced buttons, the portion of the waistband on the extension 3 being provided with a set of buttons 11, and the portion of the waistband on the extension 3' with a set of buttons 11'. Each of the straps 10, 10' is provided at its end with a button-hole 12 enabling the strap to fasten onto any one of the buttons of the respective set of buttons with which it is brought into engagement, depending upon the adjusted length of the waistband; the end of the strap 10' fastening onto any one of the buttons in the set 11, and the end of the strap 10 fastening onto any one of the buttons in the set 11'. In order that both straps may overlap the exterior of the respective waistband extensions and be attachable to fastenings on the exterior thereof, the strap 10' is passed from a point underlapping the strap 10, through this strap, by way of a slot 13 formed therein, when the strap 10' will be brought to overlap that portion of the waistband carrying the set of buttons 11, and thereby enable the end of the strap to fasten onto any one of these buttons. Thus the finish of the garment at the waistline is maintained, and provision is made for the retention

of the panel 5, as will later be referred to, when in its normal upturned position.

When the waistband is in most constricted form the respective ends of the straps will fasten onto the outermost buttons of the respective sets of buttons on the waistband, substantially as shown in Fig. 1. The waistband may now be extended by unfastening the ends thereof, and fastening them onto other buttons of the respective sets of buttons, the end of each strap fastening onto a button occupying the same relative position in the set.

The rows of buttons on the waistband, not only occupy a certain relative position to each other on the respective portions of the waistband to which they are affixed, in order that the waistband may be let out or taken in in orderly manner and all parts lie smooth, but they also occupy a certain relative position to the panel 5. As previously explained, the panel is adaptable to be turned up and be held in position to close the front of the garment and form the plackets 6 along the sides, and it is some ones of these buttons of the respective sets of buttons 11, 11' onto which the panel is adapted to fasten. The panel, along its free edge, is provided with a finishing band 14. This band is provided at its ends with horizontally extending buttonholes 15, extending in the general direction of the circumferential adjustment of the waistband. The length of the finishing band 14 on the panel and distance between its buttonholes 15, 15, corresponds with the distance around the body of the wearer, as the garment is worn, between some pair of buttons of the respective sets of buttons 11, 11'. When the waistband is in its most constricted adjusted position the panel will fasten onto the outermost ones of the buttons which make up the respective sets of buttons on the waistband. The thread holding these buttons will, as shown in Fig. 1, then occupy positions at the inner extreme ends of the respective buttonholes 15, 15 on the finishing band 14 of the panel.

It will now be assumed that the straps on the waistband are unbuttoned and fastened onto the next pair of buttons of the respective sets of buttons. These buttons are occupying a normal position at the fore sides of the wearer, consequently when change in adjustment is made, any extension measured laterally will be less than the change measured circumferentially. Accordingly the panel may still fasten onto the same extreme ones of the buttons, in the respective sets of buttons on the waistband, but at such time the thread which holds these buttons onto which the fastening is being made, will then occupy a position as shown in Fig. 3, at the outer ends of the respective buttonholes 15, 15 in the finishing band 14 to the panel.

As the waistband is continued to be let out the panel will fasten onto some pair of buttons of the respective sets of buttons 11, 11'. In Fig. 6 the garment is shown in condition where the waistband has been fully expanded within the limits afforded by the construction where the strap 10' is passing through the slot 13 in the strap 10. A slight further extension may be obtained, as shown in Fig. 8, where it will be seen that the strap 10' has been withdrawn from the slot 13 in the strap 10 and the strap 10 has been passed through a slot 16 in the strap 10'.

As the waistband is let out the panel will always fasten onto some two buttons having the same relative position in the respective sets of buttons, and lying substantially the same distance

apart as the distance that separates the buttonholes 15, 15 on the panel band 14. In consequence the panel will always occupy, when fastened, its normal position, without distortion, and thereby present at all times a finished front, covering not only the front of the garment, but also the straps to the waistband. In this connection it will be observed that the finishing band 14 on the panel has substantially the same finish or appearance as the waistband, so that when the panel is in its upturned closed position its finishing band will appear to be a part of the waistband.

I claim:

1. In a garment of the class described having back and lower portions, the combination comprising extensions connected to the back each with waistband extension at the front and straps extending, respectively, therefrom, one of said straps having a slot in it whereby one strap may be passed through the slot in the other strap and both straps overlap the exterior of the respective waistband extensions and be attachable to fastenings on the exterior thereof, sets of spaced fastenings circumferentially arranged, respectively, on the exterior of said waistband extensions, means whereby said straps when overlapping the waistband extensions as aforesaid may fasten onto certain fastenings in said respective sets of fastenings dependent upon the adjusted expansion of the garment at the waistline, a front panel movable to cover said extensions and straps when said panel is occupying a normal upturned position, and spaced fastenings borne by said panel attachable to certain fastenings in said respective sets of fastenings whereby said panel may maintain its normal upturned position without distortion irrespective of the expansion of said garment at the waistline within the limits afforded by the adjustable retention of said straps.

2. In a garment of the class described having back and lower portions, the combination comprising extensions connected to the back each with waistband extension at the front, and straps extending, respectively, therefrom, one of said straps having a slot in it whereby one strap may be passed through the slot in the other strap and both straps overlap the exterior of the respective waistband extensions and be attachable to fastenings on the exterior thereof, means for adjustably retaining said straps whereby the garment may be supported and made adjustably expansible at the waistline including separate sets of spaced fastenings circumferentially arranged on the exterior of said respective waistband extensions, and with certain of which fastenings said straps connect, respectively, when said straps are overlapping the waistband extensions as aforesaid dependent upon the adjusted expansion of the garment at the waistline, a front panel movable to cover said extensions and straps when said panel is occupying a normal upturned position, and spaced fastenings borne by said panel attachable to certain fastenings in said respective sets of fastenings whereby said panel may maintain its normal upturned position without distortion irrespective of the expansion of said garment at the waistline within the limits afforded by the adjustable retention of said straps.

3. In a garment of the class described having back and lower portions, the combination comprising extensions connected to the back each with waistband extension at the front, and straps extending, respectively, therefrom, each of said

straps having a slot in it whereby one strap may be passed through the slot in the other strap and both straps overlap the exterior of the respective waistband extensions and be attachable to fastenings on the exterior thereof, means for adjustably retaining said straps whereby the garment may be supported and made adjustably expandable at the waistline including separate sets of spaced fastenings circumferentially arranged on the exterior of said respective waistband extensions, and with certain of which fastenings said straps connect, respectively, when said straps are overlapping the waistband extensions as

5 aforesaid dependent upon the adjusted expansion of the garment at the waistline, a front panel movable to cover said extensions and straps when said panel is occupying a normal upturned position, and spaced fastenings borne by said panel attachable to certain fastenings in said respective sets of fastenings whereby said panel may maintain its normal upturned position without distortion irrespective of the expansion of said garment at the waistline within the limits afforded by the adjustable retention of said straps.

AUSTIN J. BONO.
